(57) **CLAIM**

The ornamental design for a massage chair, as shown and described.

DESCRIPTION

FIG. 1 is a perspective view of the design according to the invention.

FIG. 2 is a right side view of the design according to the invention.

FIG. 3 is a rear view of the design according to the invention.
FIG. 4 is a front view of the design according to the invention.

FIG. 5 is a bottom view of the design according to the invention.

FIG. 6 is a top view of the design according to the invention.
FIG. 7 is a right side view in an alternative position of the design according to the invention.

FIG. 8 is a right side view in an alternative position of the design according to the invention; and,
FIG. 9 is a right side view in an alternative position of the design according to the invention.

The left side view is a mirror image of the right side view.
